UNITED STATES PATENT OFFICE

ERICH SCHINSCHOLL, OF CINCINNATI, OHIO

EGG CARTON

Application filed September 6, 1928. Serial No. 304,328.

It is the object of my invention to provide an egg carton comprising a plurality of groups of egg-pockets and means whereby said egg carton may be readily divided into 5 sectional egg cartons, each comprising a group of egg-pockets; further, to provide an egg carton with novel means whereby the egg carton may be divided lengthwise for forming a tray; and, further, to provide an 10 egg carton with novel fastening means so arranged as to prevent injury in tying, untying and handling the carton.

The invention will be further readily understood from the following description and 15 claims, and from the drawings, in which latter:

Fig. 1 is a perspective view of my improved device in assembled relation.

Fig. 2 is a longitudinal section of the same, 20 taken on the line 2—2 of Fig. 1.

Fig. 3 is a cross-section of the same, taken in the plane of the line 3—3 of Fig. 2.

Fig. 4 is an inside view of my improved device in partially spread relation.

25 Fig. 5 is a plan view of the fastening means for the carton.

Fig. 6 is a bottom view of the same.

Fig. 7 is a cross-section of the same, taken 30 on the line 7—7 of Fig. 5; and,

Fig. 8 is a perspective view of a divided 35 carton section containing eggs and serving as a tray.

The carton is formed of straw board or 40 other fiber board and is exemplified as formed into cylindrical containers, a pair of which are arranged side by side, each of the cylindrical portions being arranged to contain in practice a half dozen eggs so that as shown the carton holds one dozen eggs. The invention is of course applicable to other sizes of cartons.

In its preferred form the shell of the carton 45 comprises substantially semi-cylindrical portions 12, 13, and 14, 15, arranged to be placed opposite to each other for forming the substantially cylindrical egg-containing portions of the shell.

The shell is preferably formed in one piece, 50 the portions in which the semi-cylindrical sections are formed being hinged together by

a flexible score 16, so that the halves of the shell may be opened and closed for insertion and removal of the eggs.

The semi-cylindrical portions 12, 13, have the bent portions 17 between them, and the 55 semi-cylindrical portions 14, 15, have the bent portion 18 between them.

Nests 21, 22, are provided for the respective halves of the carton, and comprise sheets of the carton provided with pockets 23, 24, 60 which mate each other in the respective halves of the carton, for receiving the respective halves of the eggs therein, and holding the eggs securely in individual pockets and separating the eggs from each other. The pockets 23, 24, are preferably formed as sectors 65 pressed from the body of the sheet forming the carton.

These nests extend lengthwise of the semi-cylindrical portions of the carton, and are 70 preferably arranged in groups 25, 26. There are six pockets shown in each of the lengthwise rows, which may constitute two groups. The collective pockets may for instance accommodate one dozen eggs, and each group 75 of pockets accommodate a half dozen eggs, arranged in threes, side by side.

The longitudinal edges of the sheets are provided with flanges 27, 28, bent therefrom along scores 29, 30, respectively resting upon the inner peripheries of the respective semi-cylinder sections 13, 15, of the shell, so as to support the respective nest-halves on the respective shell-halves along the outer margins of the respective pocket-sheets of the carton. The flanges 27, 28, extend at substantially right angles from the respective sheets of the nests and thereby strengthen said nests. The intermediate bent portions 17, 18, of the respective pairs of shell-halves preferably find support upon said nest-halves between the respective lines of pockets therein.

The carton is provided with a line of incisions 35 extending transversely of the carton, these incisions being shown in the semi-cylindrical sections, the pocket-sheets and the flanges, and are located between the respective groups of pockets. These incisions or scoring provide means whereby the egg carton may be readily divided into a plural.

ity of sectional egg cartons, as by manually breaking the carton along the line of said incisions or scoring, with or without the eggs therein, for instance, when a customer buys only a portion of the number of eggs in the carton. Instancing that a carton comprises pockets for a dozen eggs, the transverse incisions or scoring may be made in the middle of the length of the carton, for dividing the 10 carton into two egg-carton sections, each arranged for a half dozen eggs.

The outer face of the carton is provided with a line 37 extending lengthwise of the carton at the score 16, and with a line of incisions 38 extending lengthwise of the carton at said score from the inside of the carton. The line and incisions are preferably at coincident positions at opposite sides of the body of the score. The carton or carton sections are readily divided along said incisions 38, or scores, so as to readily use one-half of the carton or carton section as a tray, in which the goods are located, for instance, after the customer has the carton with its contents at 25 home and desires to place the eggs in the refrigerator or to use the same.

This enables either half of the carton or carton section to be employed as a tray in which the goods are located, the tray being 30 supported by the outer bulging portions of the semi-cylindrical portions of the shell, there being two of these semi-cylindrical portions shown in the exemplification in Fig. 8.

Each of the carton sections is provided with 35 fastening means, so that the cartons may be filled with eggs in their assembled form, for instance, containing a dozen eggs, so that if a customer desires a half-dozen eggs, the carton may be divided along the transverse incisions 40 into sections each containing a half dozen eggs, tied in the carton section, and one of these carton sections with the eggs therein delivered.

The tying means are exemplified for 45 instance as comprising a fiber washer 41. A clamp 42 has prongs 43 struck up therefrom. These prongs are received through slots 44 in the fiber washer and through slots 45 in the fiber carton. One end of a string 46 is received between the washer and the carton, and the ends of the prongs are bent outwardly, 50 toward the body of the clamp, upon the inner face of the carton, for clamping the clamp, the washer, the string and the carton together.

The edge of the washer or button is slightly 55 raised from the carton, the washer being preferably fastened to a rounding portion of the carton. The washer is shown as a round disk, and the clamp is struck up from a smaller round disk. The string is received about the carton, and then wound under the washer about the prongs, and is thereby frictionally held in place for tying the carton section. 60 Danger of contact with sharp or metal edges 65 by the seller and user is avoided.

Having thus fully described my invention, what I claim as new, and desire to secure by Letters Patent, is:

1. An egg carton comprising a shell embodying a pair of substantially semi-cylindrical longitudinally extending shell-sections forming longitudinally extending shell-halves hinged together by a score integral in said shell at the proximate sides of said substantially semi-cylindrical sections, and longitudinally extending egg-nest sections extending laterally from the opposite sides of said respective shell-sections toward said score and provided with a plurality of mating egg-pockets extending lengthwise of said shell-halves and including a plurality of longitudinally arranged groups of said mating egg-pockets, and forming a completed composite egg carton, and means for manual breaking of said completed composite egg carton into a plurality of sectional egg cartons comprising providing all said longitudinally extending portions of said completed composite egg carton with incisions extending transversely therein between said groups of mating egg-pockets for manually breaking said completed composite egg carton into said plurality of divided egg cartons on said incisions. 70 80 85 90 95

2. An egg carton comprising a shell embodying a pair of substantially semi-cylindrical longitudinally extending sections forming longitudinally extending shell-halves hinged together by a score integral in said shell at the proximate sides of said substantially semi-cylindrical sections, longitudinally extending egg-nest sections extending laterally from the opposite sides of said respective shell-sections toward said score and respectively provided with a plurality of longitudinally arranged groups of 100 mating egg-pockets extending lengthwise of said shell-sections, and longitudinally extending flanges extending from the edges of said respective egg-nest sections at said score, and arranged along the inside faces of the 110 side walls of said substantially semi-cylindrical sections adjacent to said score, and forming a completed composite egg carton, and means for manual breaking of said completed composite egg carton into a plurality 115 of sectional egg cartons comprising providing said shell-halves, said egg-nest sections and said flanges with incisions extending crosswise thereof between said longitudinally arranged groups of mating egg-pockets for 120 manually breaking said completed composite egg carton into said plurality of sectional egg cartons on said incisions. 120 130

3. An egg carton comprising a shell embodying a pair of substantially semi-cylindrical longitudinally extending sections forming longitudinally extending shell-halves hinged together by a score integral in said shell at the proximate sides of said substantially semi-cylindrical sections, longitudi- 125 130

- dinarily extending egg-nest sections extending laterally from the opposite sides of said respective shell-sections toward said score and provided with a plurality of mating egg-pockets extending lengthwise of said shell-halves and including a plurality of longitudinally arranged groups of mating egg-pockets, and forming a completed composite egg carton, and means for manual breaking of said completed composite egg carton into a plurality of sectional egg cartons comprising providing said longitudinally extending portions of said shell with incisions extending transversely thereof between said longitudinally arranged groups of mating egg pockets, for manually breaking said completed composite egg carton into a plurality of sectional egg cartons on said incisions, and separate tying means encompassing each of said sectional egg cartons. 5 70
4. An egg carton comprising a shell formed with a plurality of pairs of substantially semi-cylindrical longitudinally extending sections to form longitudinally extending shell-halves hinged together by a score integral in said shell, and longitudinally extending egg-nest sections extending laterally from said respective shell-sections toward said score and provided with pairs of mating egg-pockets extending lengthwise of and arranged to register with said plurality of pairs of said shell-halves, said egg carton arranged to be supported by the outer portions of said shell-halves, and forming a completed egg carton, 25 75
- 35 and means for manual separation of said pairs of shell-halves and constituting the same respectively as trays, comprising providing said egg carton with a longitudinally extending incision extending along said score between said plurality of pairs of shell-halves for separating said plurality of pairs of shell-halves with said egg-nest sections respectively thereon. 40 80
5. An egg carton comprising a shell embodying a plurality of pairs of substantially semi-cylindrical longitudinally extending sections to form a plurality of pairs of shell-halves hinged together by a longitudinal score integral in said shell, a plurality of 45 85
- 50 pairs of longitudinally extending egg-nest sections extending laterally from said respective shell-sections toward said score and provided with a plurality of pairs of longitudinally extending mating egg-pockets extending longitudinally arranged groups lengthwise of said respective shell-sections, and forming a completed composite egg carton, and means for manual breaking of said completed composite egg carton into a plurality 55 90
- 60 of sectional egg cartons comprising providing said longitudinally extending portions of said completed composite egg carton with incisions extending transversely thereof between said longitudinally arranged groups 65 95
- 65 of mating egg-pockets, for manually dividing 70 100
- 70 said groups of mating egg-pockets on said incisions, a tying means for each of said sectional egg cartons, said egg cartons arranged to be supported by the outer portions of said shell-halves, and means for the transforming of completed composite egg carton into a plurality of trays each of which comprises one of said plurality of pairs of shell-halves comprising providing said score with incisions extending lengthwise thereof for manual separation of said respective pairs of shell-halves on said last-named incisions. 75 105
